(57) **CLAIM**

The ornamental design for a retractable extension cord niche, as shown and described.

DESCRIPTION

FIG. 1 is a top front isometric view of a retractable extension cord niche, showing my new design, and shown in an environment;

FIG. 2 is a bottom front isometric view thereof;

FIG. 3 is a front view thereof;

FIG. 4 is a left side view thereof;

FIG. 5 is a right side view thereof;

FIG. 6 is a top view thereof;

FIG. 7 is a bottom view thereof;

FIG. 8 is a rear view thereof; and

FIG. 9 is a top front isometric view of the retractable extension cord niche in its installed state thereof;

FIG. 10 is a bottom front isometric view of the retractable extension cord niche in its installed state thereof; and,

FIG. 11 is a top front isometric view of a retractable extension cord niche, shown in an alternate position, and shown in an environment.

In FIG. 8, the broken lines depict portions of the article that form no part of the claimed design. In FIGS. 3, 9 and 10, the broken lines depict environmental subject matter that form no part of the claimed design. In FIGS. 1, 2, 4, 5, 6, 7 and 11, the broken lines depict both environmental subject matter and portions of the article that form no part of the claimed design.
